UNITED STATES PATENT OFFICE.

AUGUST S. HELD, OF FREEPORT, ILLINOIS, ASSIGNOR TO THE STOVER MANUFACTURING COMPANY, OF SAME PLACE.

DESIGN FOR A HINGE-LEAF.

SPECIFICATION forming part of Design No. 28,322, dated March 1, 1898.

Application filed January 7, 1898. Serial No. 665,981. Term of patent 7 years.

To all whom it may concern:

Be it known that I, AUGUST S. HELD, a citizen of the United States of America, residing at Freeport, in the county of Stephenson and State of Illinois, have invented a new and original Design for a Hinge-Leaf, of which the following is a specification.

My invention relates to a new and original design for a hinge-leaf which is illustrated in the accompanying drawings by means of four figures, of which—

Figure 1 is a face view; Fig. 2, a rear view; Fig. 3, a sectional view looking downward from the line 3 3 of Fig. 1, and Fig. 4 a side view looking in the direction of arrow 4.

Referring to the drawings, the portion A is substantially flat upon the back and has upon one side two laterally-extending projections *a a'*, the under surface of which is substantially a continuation of the portion A. From these projections and from the adjacent edge of the portion A rises a forward pro-

jection B, hollow beneath and having in general a sort of horizontally-rounded contour. In the face and rear views the portion B lies 25 within a line connecting the ends of the projections *a a'*.

The essential portions of my design I consider to be the portion A, substantially flat upon the under side, the projections *a a'* being substantially continuations of the flat under surface of the portion A, and the forward projection B, lying within the line joining the ends of the projections *a a'* in face and rear view. 30

I claim as new and desire to secure by Letters Patent—

The design for a hinge-leaf herein shown and described.

AUGUST S. HELD.
